UNITED STATES PATENT OFFICE.

RALPH W. AUSTIN, OF QUINCY, MASSACHUSETTS.

FIRE EXTINGUISHER.

Application filed September 17, 1923. Serial No. 663,054.

This invention relates to a fire extinguisher, and has for an object to provide a novel and improved construction of fire extinguisher, which is efficient and reliable in operation, 5 may be economically manufactured, and is easily recharged, cleaned and maintained in an operative condition.

The different features of the invention will be hereinafter described and particularly 10 pointed out in the claims at the end of the specification.

In the drawing, Fig. 1 is a vertical section of a fire extinguisher embodying the features of the present invention and Fig. 2 is a 15 section on line 2—2 of Fig. 1.

Referring to the drawing, the fire extinguisher illustrated therein comprises a metal casing 10 preferably of usual construction having an opening 12 therein and a neck 13 20 threaded and upon which the usual extinguisher cap 14 is screwed. The casing 10 is normally filled with an extinguishing liquid to approximately the level indicated in the drawing. The extinguishing liquid is dis- 25 charged during the operation of the extinguisher through a discharge nozzle 15 of usual construction by the gas pressure developed preferably by the reaction of an acid with a carbonate solution, when the extin- 30 guisher is turned into an operative position, or inverted. The carbonate solution and acid may and preferably will be contained in separate receptacles 16, 18, arranged one within the other, and the carbonate receptacle 16 35 comprises preferably a metal tube closed at one end 17 and of such diameter as to be capable of insertion into the opening 12 in the extinguisher casing. The metal tube 16 is preferably soldered or otherwise se- 40 cured to a neck ring 20 to be supported thereby and the latter is provided with an annular flange 22 which rests upon the neck 12 of the extinguisher casing and is removably clamped in such position by the extinguisher cap 14 as illustrated. The acid container 18 45 is normally closed by a stopper 28, and is supported within the metal tube 16 upon supporting members 30 soldered or otherwise secured to the interior of the metal tube, as 50 will be described. The metal tube 16 and acid bottle 18 are filled with the suitable quantities of carbonate solution and acid respectively, and when the extinguisher is inverted, the acid and carbonate flow and mix together, 55 generating carbon dioxide gas and high pressure. The upper end of the receptacle 16

is provided with an annular ring portion into which the cap 34 is screwed and which cooperates with the cap to form a closure for the upper end of the container 16. A space 38 60 is provided between the top of the cap 34 and the extinguisher cap 14, and provision is made for connecting this space 38 with the interior of the carbonate container 16 and also with the interior of the extinguisher casing 10 outside of the carbonate container 16 65 in order to permit the gas pressure generated by the mixture of the carbonate and acid solutions within the inverted upper end of the container 16 to pass to above the extinguishing liquid in the casing 10. As herein shown, one or more conduits 36 comprising preferably relatively small straight tubes are fixed at their upper ends in the annular ring portion into which the cap 34 is screwed, and the lower ends of the conduits 36 are arranged 70 to terminate at a point within the carbonate container 16 above the normal level of the carbonate solution therein, so that when the extinguisher is inverted there exists very lit- 75 tle chance of any appreciable amount of carbonate solution running down the inverted tubes 36 into the space comprising the chamber 38.

The space 38 is herein shown connected 80 with the interior of the casing 10 outside of the carbonate container 16 by one or more conduits 44 also preferably fixed at their upper ends in the ring portion into which the cap 34 is screwed, and the lower ends of 85 which extend completely through the bottom 17 of the carbonate container 16. A fluid-tight closure or joint is formed between the conduits 44 and the bottom 17 of the container 16. 90

With this arrangement of the conduits 36, 95 44, the liability of the formation of calcium carbonate resulting from the reaction of any calcium chloride which may be used in the extinguishing liquid to lower the freezing point thereof, with any carbonate solution which may find its way into the chamber 38, is practically entirely avoided. In the normal upright position of the extinguisher, it will be observed that the ends of the tubes 36 terminate above the normal level of the carbonate solution, so that when the extinguisher is inverted only a small chance is afforded for appreciable quantity of carbonate solution entering the tubes 36. Were the tubes 36 to extend down into the carbonate solution, then a slug of carbonate solution 100 105 110

would find its way into the chamber 38 when the extinguisher was inverted, and upon reaction with some of the calcium chloride solution entering through the conduit 44 upon 5 inversion of the extinguisher, would result in the clogging of the space 38 and rendering the extinguisher inoperative. With the present construction any calcium chloride solution which finds its way into the chamber 10 38 and into the interior of the tubes 44 is immediately blown out by the gas pressure when the extinguisher is operated.

The acid, as has been stated, is normally contained in an acid bottle 18 supported with- 15 in the metal tube 16 upon a bottle supporting member 30 which may and preferably will comprise a spider having arms 50 provided with semi-cylindrical portions 52 upon the ends thereof, which fit and are soldered or 20 otherwise secured to the metal tubes or conduits 36 and 44. The spider 52, it will be observed, enables the carbonate solution to readily flow downwardly through the openings formed between its arms and around 25 the sides of the acid bottle when the extinguisher is inverted. Provision is made for maintaining the acid bottle in a central position within the metal tube 16 and for this purpose a supporting ring 40 is provided, which 30 is soldered to the metal tubes 36, 44. The acid bottle 18 is preferably supported when the extinguisher is inverted by a supporting ring 54 arranged to engage the neck portion of the bottle. The supporting ring 54 is illus- 35 trated as secured upon the ends of a plurality of rods 56 carried by and depending from a cap 34, screwed into the annular ring portion to completely close the upper end of the metal tube 16. The cap 34 is provided with a 40 cylindrical portion 58 which cooperates with a projection or boss 60 upstanding from the top of the stopper 28 to guide the latter in its movements. The stopper is preferably pro- 45 vided with a boss or projection 62 depending from the under side thereof of sufficient length to extend into the mouth of the bottle in all positions of the extinguisher to insure seating of the stopper upon the bottle when the extinguisher is brought into an upright 50 position after having been inverted.

In operation, when the extinguisher is inverted the carbonate solution within the metal tube 16 flows downwardly around the acid bottle 18 and mixes with the acid emerg- 55 ing from the mouth of the inverted bottle, in the inverted closed upper end of the carbonate container 16. The carbonate and acid react to form carbon dioxide gas and the gas pressure developed passes through the 60 conduits 36 through the space 38 and thence upwardly through the conduits 44 to above the extinguishing liquid within the casing 10.

In the event that calcium chloride or other salt having the desired effect be dissolved 65 in the extinguishing fluid to lower the freez-

ing point thereof, the present construction of extinguisher prevents the calcium chloride solution from coming in contact with the carbonate solution so that clogging of the extinguisher by precipitated calcium carbonate or 70 other insoluble salt is avoided. The small quantity of calcium carbonate formed by the carbon dioxide gas passing through the relatively small head of extinguishing liquid upon leaving the conduit or conduits 44 is 75 insufficient to have any appreciable effect upon the operation of the extinguisher. It will also be apparent that the construction of the carbonate receptacle 16 is such that it may be made economically, and easily and 80 conveniently cleaned. The conduits or tubes 36, 44, it will be observed, are straight so that an operator may insert a brush or other instrument directly into the same to force any obstructing material therefrom. In this 85 manner the extinguisher may be maintained in a highly efficient condition and easily and economically recharged. In order to minimize corrosion, in practice the interior of the extinguisher casing and the carbonate 90 receptacle including the tubes 36, 44 will be plated with nickel or other suitable non-corrodible material.

While the preferred embodiment of the invention has been illustrated and described, 95 it will be understood that the same may be embodied in other forms within the scope of the following claims:

1. In a fire extinguisher, in combination, a casing for containing an extinguishing liquid having an opening therein, a neck surrounding said opening, a cap for closing the opening, and means for generating gas pressure within the casing including a closed container adapted to contain a carbonate solution, said container being supported upon said neck between it and the cap, and arranged to provide a chamber between the top of the container and said cap, an acid receptacle supported within said container, and two sets of relatively small straight tubes secured to said carbonate container, one set of tubes connecting said chamber with the interior of the carbonate container and terminating above the normal level of the carbonate liquid therein, and the second set of tubes connecting said chamber with the interior of the extinguisher casing outside of said carbonate container for transmitting the gas pressure generated upon inversion 110 of the extinguisher to above the extinguishing liquid.

2. In a fire extinguisher of the type employing acid and carbonate solutions for generating gas pressure, in combination, a 115 casing for containing the extinguishing liquid provided with an opening and a removable cap therefor, a closed carbonate container positioned within the casing to form a chamber between it and the extinguisher 120 130

cap, an acid container within the carbonate container, a substantially straight tube connecting said chamber with the interior of the carbonate container, one end of said tube 5 terminating above the normal level of the carbonate liquid, and a second substantially straight tube leading from said chamber for conducting generated gas to above the extinguishing liquid in the casing, when the 10 extinguisher is in inverted position.

3. In a fire extinguisher of the type employing acid and carbonate solutions for generating gas pressure, in combination, a casing for containing the extinguishing liquid provided with an opening and a removable cap therefor, a closed carbonate container positioned within the casing to form a chamber between it and the extinguisher cap, an acid container within the carbonate 15 container, and a conduit connecting said chamber with the interior of the carbonate container and terminating above the normal level of the carbonate liquid, and a second conduit leading from said chamber for conducting generated gas to above the extinguishing liquid in the casing when the extinguisher is in inverted position.

4. In a fire extinguisher of the type employing acid and carbonate solutions for

generating gas pressure, in combination, a 30 casing for containing the extinguishing liquid provided with an opening and a cap removably closing the opening, an elongated carbonate container closed at its bottom, positioned within the casing, and capable of 35 removal from within the casing through the opening therein, an acid container within the carbonate container, said carbonate container being secured in the casing to form a chamber between the top of the carbonate container and the cap, an annular ring member 40 forming a part of the closure for the upper end of the carbonate container, and a cap in threaded engagement with the ring member forming the remainder of the closure for the 45 upper end of the carbonate container, and two conduits both fixed at their upper ends in said ring member, one extending within the carbonate container and terminating at a point located above the normal level of the 50 carbonate solution therein, the other conduit extending through said container for conducting generated gas to above the extinguishing liquid within the extinguisher casing when the extinguisher is in inverted 55 position.

RALPH W. AUSTIN.
